UNITED STATES PATENT OFFICE

NILS O. LINDSTROM, OF NUTLEY, NEW JERSEY, ASSIGNOR TO A. B. SEE ELEVATOR COMPANY, INC., A CORPORATION OF DELAWARE

ELEVATOR DOOR SYSTEM

Application filed July 23, 1927. Serial No. 207,831.

My invention relates to elevator door devices, and particularly to elevator doors including means for the automatic closure thereof, and a safety switch for preventing operation of the elevator car when the door is open.

For purposes of safety, it is essential that the shaftway and car doors of elevators, particularly the fully automatic or push button elevators, be so protected that the doors can be opened only when the car is stopped at a given floor, and so that the elevator car cannot be moved from a floor until the doors are closed. Safety devices of this general type are customary and essential parts of all modern elevator systems, and many elaborate and complicated systems have been built in attempts to provide the desired degree of safety. All of the previous systems are, however, unduly elaborate, complicated, and subject to disablement such that the elevator as a whole becomes inoperative.

My invention provides an extremely simple door control system, adapted to be used with elevator systems in general and particularly adapted for the fully automatic type of elevator, which system provides the necessary safety with a minimum number of parts of the greatest simplicity. By the device of my invention, I am enabled to provide for the closure of all of the elevator shaftway doors through the agency of a single spring or weight, and to operate a single electric circuit switch for stopping the elevator motion by locking out the power connection thereto, from any of a number of shaftway doors. Likewise my device is particularly adapted to the fully automatic elevator system in which power means for actuation of the car door is provided. It provides means whereby the opening of the car door, simultaneously opens the shaftway door at which the car is positioned, but opening it only if the elevator is leveled off at the floor. My invention further provides means for the controlled closure of the elevator shaftway door at a slow speed, to prevent injury to a passenger. The system of my invention further contains a minimum number of rugged

parts of the greatest simplicity and durability.

By the device of my invention I thus provide an inexpensive, simple, durable, rugged, elevator-door gear adapted to the meeting of all of the needs of a fully automatic system, as well as the needs of simpler systems.

Other objects and structural details of my invention will be apparent from the following description when read in connection with the accompanying drawings, wherein:

Fig. 1 is a view in side elevation partly in section of an elevator system embodying the device of my invention;

Fig. 2 is a front view, partly diagrammatic, of the same embodiment;

Fig. 3 is a plan view in partial section of the same embodiment;

Fig. 4 is a front view of the same embodiment showing a door in opened position;

Figs. 5 and 6 are side elevations of detail modifications, and

Fig. 7 is a diagram showing the application of the invention to an elevator of the push button automatic electrically controlled type.

Referring to the figures, I provide a shaftway 1 having guides 2 and a car 3. Doorways are provided at the respective floor levels of the elevator shaft, closed by doors which may desirably consist of pairs of sliding doors 4 and 5. The elevator car 3 is likewise desirably provided with a suitable door member 6 which may consist of a folding lattice door structure, or may consist of a pair of sliding doors similar in general pattern to the shaftway doors. A door opening and closing device may be provided in connection with the car door, according to the system disclosed in the copending application Serial No. 138,453, filed in the name of Carl F. E. Olofson and myself, assigned to the A. B. See Elevator Company.

The shaftway doors 4 and 5 are desirably supported upon roller carriages, so that they open and close readily. A lever system is provided in connection with the doors, for the purpose of controlling their movements. This lever mechanism may desirably consist of a first lever 7 pivoted by a pivot mem-

ber 8 to the shaftway wall. A second lever 9 is desirably pivoted at 11 to the end of the lever 7, and at 12 to the movable door. The lever 9 has an extension 14, in the form of a bell crank lever, upon which may desirably be mounted a roller 15. The lever 7 may desirably have a tail lever member 16 and a counterweight 17. A tension device such as a vertical rod, or ribbon member 18 is desirably provided extending the length of the shaftway. The tension or ribbon member 18 is desirably supported by a spring 19, of medium strength, which may be described as a "10 lb. spring". At the bottom of the ribbon member 18 is positioned a dash pot member 21 consisting of a cylinder 22, piston 23, and control valve 24. The ribbon member 18 is attached to the piston 23, and a spring 25 is provided for producing a downward movement of the piston 23 and attached ribbon member 18. The spring 25 is desirably considerably stronger than the spring 19, and may be described as a "30 lb. spring". Along the length of the ribbon 18, at appropriate points in each floor level, are attached a plurality of collar members 26. The collar members may be adjustably fastened by screws 27 as indicated, or they may be fastened permanently in place by pins or rivets. Cooperating with the attached collars 26 are movable collars 28, surrounding the ribbon member 18, and positioned just below the fixed collars 26. Between the collars 28 and the door-lever tail-member 16 are attached connector members 29 which may take the form of tension devices such as lengths of chain or may take the form of suitable bar members. At a convenient point along the length of the ribbon 18, which may desirably be near the upper end, is positioned a safety switch member 31, adapted to be opened by an upward movement of the ribbon member 18. The car door, which may be constructed according to the disclosure in the previously mentioned copending application, desirably has a door guide member 32. A slide member 33 cooperating with the guide 32 is desirably attached to the leading edge of the car door 6. A motor 34 and chain 35 according to the disclosure of the previously mentioned application, are likewise also desirably provided for the automatic actuation of the gate 6. Upon the slide member 33 is positioned a carrier plate 36, adapted to engage with the roller 15 upon the end of the bell crank 14 for opening the doors 4.

For the operation of my device, the elevator system may, if desired, be made fully automatic as indicated in Fig. 7, so that upon the pushing of any floor button 40 by a passenger the elevator mechanism is brought into operation, and the car carried to the appropriate floor. Upon stopping at the floor, the motor 34 is energized by appropriate

means to open the doors. The movement of the chain by the motor 34 carries the slide 33 and the plate 36 in an appropriate direction to open the car door, in the instance shown, toward the right. The plate 36 cooperates with the roller 15, and through the agency of the bell crank lever 14 moves the bar 9 downward, and with it the bar 7, thereby freeing the toggle joint at the pivot 11 and permitting the door portion 4 to open. Simultaneously the tail lever member 16 is carried upward by the movement of the lever 17 and carries with it the chain member 29 and the collar 28. This upward movement lifts the ribbon against the pressure of the spring 25 and the portion of the ribbon above the collar 28 is lifted by the spring 19, to open the contact 31, thereby locking out the starting contactor on the motor panel board. A single door may be opened at a time, and the ribbon 18 lifted without disturbance of the corresponding members at the other doors because of the free movement possible between the collars 28 and the ribbon which form a release mechanism. The members 26 at the closed doors are simply lifted away from the corresponding collars 28, and the door levers are held in closed position by the counterweights 17.

By this means the car door and an appropriate shaftway door are opened for the access of passengers. The position taken by the levers when the door is fully opened is shown in further detail in Fig. 4 where the plate 36 is shown pulled to the right, the levers 7 and 9 are shown folded downward behind a portion of the door, and the ribbon 18, and the collars 26 and 28 are shown lifted to the full upward position for the opening of the contactor 31.

The passengers may then enter the car and press the car button to indicate the floor to which they desire to go. Pressure of the car button energizes the motor 34 in the reverse direction and moves the door 6 to the closed position. The movement of the door, and with it the slide 33, carries the plate 36 away from the roller 15. This removes the pressure upon the bell crank lever 14 and frees door 4. The downward pressure of the spring 25 upon the ribbon 8 is then effective through the collar 26, the collar 28, the chain 29 and the lever tail 16 to swing the levers 7 and 9 into the position shown in Fig. 2, for the closure of the shaftway door. As the door 4 closes, the ribbon 18 moves downwardly until, when the door 4 is substantially closed, a circuit is closed by the device 31 to energize the main elevator motor and the associated winding gear. The elevator gear then moves the car to the desired floor, and stops, whereupon the motor 34 is energized in the direction first described, and pulls the chain 35 to open the car door 6, and the ap-

propriate shaftway door 4 as previously described, for the egress of the passengers.

All of the elevator doors are thus controlled by a single spring closing member, 5 and the opening of any door stops the movement of the elevator through the opening of a single circuit device. This construction is particularly advantageous, because of the fact that it reduces the maintenance required 10 upon electrical safety devices, a single one only being required as distinguished from one for each shaftway door of the prior art. The construction is further highly advantageous because of the fact that all the doors 15 are closed by the same moderately powerful spring. This construction makes it impossible for a passenger to be caught in the doorway and injured by unduly high tension upon the door closing device. Likewise 20 the doors are closed slowly because of the presence of the dash pot 21. The fact that a single dash pot only is used for all of the doors is advantageous, since it reduces the cost. Also the dash pot is located in an 25 advantageous place, being at the bottom of the shaftway, conveniently available for inspection and maintenance, and in a position where there is ample room for a dash pot of adequate size. The dash pot thus is desirably 30 constructed in a rather large size, with relatively large fluid passages. This construction prevents the fouling of the passages and faulty operation of the dash pot through the presence of dirt or other ob- 35 structive matter.

I have described the operation of my invention as applied to a fully automatic elevator system. It is, however, equally well adapted to a manual elevator operating system of the usual type. In such an embodiment, the car may be operated by a control lever under the hand of an operator, who also opens and closes the elevator gates. In my construction, the opening of the car gate 45 by the operator simultaneously opens the shaftway gate, without the necessity for a separate operation. Likewise the shaftway gate closes slowly, easily, and automatically upon the closure of the car gate by the operator. Such a system likewise has advantages in speed of operation, and safety and certainty of handling.

It is, of course, desirable that appropriate circuit switches be provided in connection 50 with the car gate as well as with the shaftway gates. Such safety devices may, however, take the form shown in my copending application, and need not be here described.

The bell crank lever 14 may, as previously suggested, be made as an integral part with the lever 9. Such construction is however not entirely desirable, because of the fact that it results in a smaller amount of movement of the door 4 than of the door 6. The bell crank lever 14 is desirably made sepa-

rate from the lever portion 9, pivoted upon the same pivot 12, and adapted to cooperate with the lever 9 by means of a stop 40, so that the pressure of the plate 36 upon the roller 15, moves the lever 14, and with it the 70 lever 9 downward, enough to break the toggle joint lock between the levers 7 and 9. A stop 41 is desirably provided attached to the door 4 and cooperating with the bell crank lever 14 to limit its motion so that enough movement of the lever 14 is allowed to break the toggle lock, and no more. Such construction permits the application of pressure from the plate 36, through the roller 15, lever 14 and the stop described, to carry the door 4 towards the open position, the levers 9 and 7 moving together in an appropriate manner. This construction is shown in Fig. 4.

The construction disclosed utilizes a relatively light spring at the upper end of the ribbon 8, and a heavier spring 25 at the lower end of the ribbon. The spring 25 may be replaced by a counterweight if desired, as for example by increasing the weight of the piston 23 and eliminating the spring 25 although the speed of operation when so constructed is not as great. Likewise the spring 19 may be replaced by a lever 42 and counterweight 43, as shown in Fig. 5.

The safety switch, or lockout switch 31, is desirably positioned near the top of the ribbon 18, since when so positioned it will function to stop the elevator in the event that the ribbon 18 should break. Breakage of the ribbon releases the spring 19 and permits it to lift the contact members 31. This operation can fail only in the event that the ribbon breaks between the switch 31 and the spring 19, which is extremely unlikely. However to avoid any such possibility, the switch 31 may be mounted directly above the spring 19 as in Fig. 6, thereby reducing the possibility of failure to a vanishingly small value.

A detailed wiring diagram of the electrical circuits is shown in Figure 7, which for the sake of simplicity and clearness, shows an automatic elevator system involving only two floors or landings and omits the electrical control within the car, the hoisting motor and its connections from reversing switches, and various other circuits well known and in common use.

In the wiring diagram, the source of current is the main line wires 44 and 45. There is a push button for each floor landing 46 and 46'. Since there are only two floors, each push button will cause the elevator to move in only one direction. In case the system includes more than two landings, a floor selecting device (not shown, but well known) will be connected to the various push buttons in order to enable each push button to bring the elevator car to its landing no matter where it may be positioned in the shaft; that is, the 130

car will sometimes be moved upward and sometimes downward by a single push button in order to bring it to the floor controlled by such push button as when the push button is on a floor intermediate the top and bottom floor landings. In any case, the elevator gate will be automatically brought to a closed position by closing the push button circuit before the hoisting motor is operated, and when the elevator reaches the desired floor landing, the elevator gate, and the shaftway door will be automatically opened as will now be described.

There is a relay associated with each push button, its energizing coil being in a circuit closed thereby. As shown, the relay 47 associated with the push button 46 will upon movement of the push button 46 be energized by a circuit as follows: from line wire 44 through wires 48, 49, 50, relay coil 47, wire 51, relay arm 52, contact 53, wire 54, push button 46, wires 55 and 56, contact 57, arm 58, and wires 59 and 60 to line wire 45. The relay 47 is thereby energized and the conducting arms 61 and 62 thrown to the left whereby the circuit through the push button 46 is opened at 53 and a circuit closed as follows: from line wire 44, to arm 52 as before, thence through arms 61, 62, and 63, wire 64, resistance 65, wires 66, 67 and 68, relay coil 69, wire 70, relay arm 71, contact 72, wire 73 to line wire 45.

The energizing of relay coil 69 causes the conducting arms 74 and 75 to be thrown to the left, separating arm 58 from contact 57 and thereby making it impossible to close a circuit through either of the push buttons 46 or 46'. Furthermore, the contacting of arm 75 with arm 76 causes the closing of a circuit from wire 68 through wire 77, relay coil 78, wire 79, contact 80, arm 81, wires 82, 83 and 84, arms 76, 75, 74, and 58 and wires 59 and 60 to line wire 45.

The energizing of relay coil 80 causes the conducting arms 85 and 86 to be thrown to the left and a circuit to be closed as follows: from line wire 44 through wires 48 and 87, contact 88, arm 89 of reversing switch R, series field windings 90 of gate motor 34, lead 91, motor armature and lead 92, part of the current being shunted through resistance 93, thence through resistance 94, arm 95, contact 96, wire 97, arms 98, 86, 85 and 99, wire 100, contact 101, arm 102, wire 103, arm 104, contact 105, wires 106 and 60 to line wire 45. The motor 34 also has a shunt field winding 107 connected across from wire 87 to arm 85, as shown.

The result of the closing of the circuits just described is the starting of the gate motor 34 which causes the traversing of the elevator car gate from its open position as shown in Figure 4, toward the left until the contact bar 108 of the elevator gate switch 21 is shifted from the upper contacts 109 to the lower con-

tacts 110. The gate switch is such that when the gate reaches the open position the contact bar 108 is moved to close the circuit between upper contacts 109, and when the gate reaches the closed position, the bar 108 is moved to close the circuit between the lower contacts 110 which causes the opening of the circuit through the gate motor and operates the reversing switch R so that when the elevator reaches the desired floor landing, the motor connections will be such that when the motor is energized, it will traverse the gate from the closed to the open position.

The connections between the contacts 110 will establish a circuit as follows: from line wire 44, through wires 48, 49 and 50, relay coil 47, wire 51, arms 52, 61, 62, and 63, wire 64, up limit switch 111, wire 112, contact 113 of down reversing switch R', resistance 114, wires 115 and 116, relay coil 117, wire 118, contact bar 108 of the elevator gate switch 21, wires 83 and 84, arms 76, 75, 74 and 58, and wires 59 and 60 to line wire 45. The effect of the energizing of the relay coil 117 is to throw the arms 119 and 121 to the left thus causing the opening of the gate motor circuit at 101 and 105 and stopping the gate motor. The arm 120 is also thrown to the left, thereby separating 80 and 81, deenergizing relay 78 and opening the gate motor circuit at 85 and 86. Furthermore, a circuit is completed from line wire 44 through wire 122, relay coil 123 of gate motor reversing switch R, wire 124, switch 21, wires 83 and 84, arms 76, 75, 74 and 58, and wires 59 and 60 to line wire 45. The effect of energizing coil 123 is to actuate the reversing switch R to change the connections to the armature of the gate motor 34 to reverse the direction of rotation of the elevator gate motor 34 when it is again energized.

The arm 120 by contacting with the arm 81 closes a circuit as follows: from line wire 44 to contact 113 of down reversing switch R' as before, thence through wire 125, coil 126 of up reversing switch R'', wire 127, coil 128 of potential or circuit breaking switch, wire 129, locking out switch 31, wire 130, arms 120 and 81, wires 82, 83 and 84, arms 76, 75, 74 and 58, and wires 59 and 60 to line wire 45. The effect of the closing of such circuit is the closing by the reversing switch R'' of the hoisting motor circuit (not shown) thereby causing the motor to raise the elevator from its lower to its upper position level with the landing upon which push button 46 is situated. As it reaches that landing, it causes by well known means, the opening of the up limit switch 111 and thereby opens the hoisting motor circuit and stops the elevator car; it also causes the deenergizing of the relay coil 117.

The deenergizing of the coil 117 permits arms 119 and 120 to be returned to their original position, thereby establishing a cir-

cuit to relay coil 78 and to the elevator gate motor 34. Since the relay coil of the reversing switch R of the elevator gate motor 34 is energized as hereinbefore described, the elevator gate motor will operate to traverse the gate from the closed to the open position, the shaftway door being simultaneously opened as hereinbefore described. The opening of the elevator gate will cause contact bar 108 to close the gap between contacts 109 and open the circuit between contacts 110.

The opening of the circuit between contacts 110 will deenergize the relay coil 123.

The connection between the contacts 109 will cause a circuit to be closed as follows: from line wire 44, through wire 131, contact bar 108, wire 182, relay coil 133, wire 84, arms 76, 75, 74 and 58, and wires 59 and 60 to line wire 45. The energizing of coil 133 causes the arm 71 to be thrown to the right, thereby deenergizing coils 69, 47 and 133 and restoring the various parts to their original positions.

The circuits controlled by push button 46' are similar in all respects to those described in connection with push button 46 and the operation is the same except that the reversing switch R' will so connect the hoisting motor as to cause the elevator car to descend until it reaches the landing upon which push button 46' is located, at which time the elevator car causes the opening of the down limit switch 134 and energizes the various relays as before.

By the device of my invention I am thus enabled to provide a highly satisfactory elevator door control system, having much fewer, and simpler, and more rugged parts than the devices of the prior art. The door control device of my invention is likewise highly suitable for automatic operation, and when so operated provides the utmost convenience and safety. The device also is extremely simple and easy of maintenance.

While I have shown but a single embodiment of my invention in the figures, and have described but two embodiments, it is capable of embodiment in still other forms without departure from the spirit thereof, and I desire, therefore, that only such limitations shall be imposed upon the scope of the claims describing my invention as are required by the prior art.

I claim as my invention:

1. In an elevator system, a shaftway having a plurality of doors opening thereto and sliding door members cooperating therewith, means comprising sets of toggle levers for controlling the movements of said doors, one of said levers of said sets having a bell crank lever portion adapted to cooperate with an opening means, and another of said levers having a counterweight and tail member, and a common tension member cooperating with the tails of said levers, and means comprising a controlled spring for applying force for the closure of said doors, and means cooperating with the common member under tension for locking out the elevator car moving means when a shaftway door is open.

2. In an elevator system, an automatic operating means comprising a push button electrical control system having means for the automatic control of the movements of said elevator, and automatic means for the opening and closing of said car door, said means being adapted to open a shaftway door simultaneously, and means other than said car door common to all of said shaftway doors for the controlled closure thereof upon actuation of said automatic members, and means associated with said closure means for locking out the car power connection when a shaftway door is opened.

3. In an elevator system, a shaftway having openings thereto at different floor landings, doors for the shaftway openings, an elevator car in the shaftway, means for moving the elevator car, a gate on the elevator car, gate operating means for moving the gate in one direction to open the gate and in the opposite direction to close the gate, means on the gate for engaging the shaftway doors to open the doors with the gate, and additional means common to all of the shaftway doors for controlling the closure thereof.

4. In an elevator system, a shaftway having openings thereto at different floor landings, doors for the shaftway openings, an elevator car in the shaftway, means for moving the elevator car, a gate on the elevator car, gate operating means for moving the gate in one direction to open the gate and in the opposite direction to close the gate, means on the gate for engaging the shaftway doors to open the doors with the gate, additional means common to all of the shaftway doors for controlling the closure thereof, and means for locking out the elevator car operating means when a shaftway door is open.

5. In an elevator system, a shaftway having a plurality of openings thereto, an elevator car in the shaftway, means for moving the elevator car, sliding doors for the shaftway openings, means comprising sets of toggle levers for each of the doors for controlling the movements of the doors, one of the levers of said sets having a bell crank lever portion adapted to cooperate with an opening means, and another of said levers having a counter weight and tail member, a common member under tension cooperating with the tails of said levers, means comprising a controlled spring for applying a force for the closure of said doors, and means cooperating with the common member under tension for locking out the elevator car moving means when a shaftway door is open.

6. In an elevator system, a shaftway having a plurality of openings thereto, an elevator car in the shaftway, means for moving the elevator car, sliding doors for the shaftway openings, means comprising sets of toggle

levers for each of the doors for controlling the movements of the doors, one of the levers of said sets having a bell crank lever portion adapted to cooperate with an opening means, and another of said levers having a counterweight and tail member, a common member under tension cooperating with the tails of said levers, means comprising a controlled spring for applying a force to the common member under tension for the closure of said doors, and means cooperating with the common member under tension for locking out the elevator car moving means when the common member is not under tension.

7. In an elevator system, a shaftway having a plurality of openings thereto, an elevator car in the shaftway, means for moving the elevator car, sliding doors for the shaftway openings, means comprising sets of toggle levers for each of the doors for controlling the movements of the doors, one of the levers of said sets having a bell crank lever portion adapted to cooperate with an opening means, and another of said levers having a counterweight and tail member, a common member under tension cooperating with the tails of said levers, means comprising a controlled spring for applying a force to the common member under tension for the closure of said doors, and means cooperating with the common member under tension for locking out the elevator car moving means when a shaftway door is open and when the common member is not under tension.

8. In an elevator system, a shaftway having a plurality of openings thereto, an elevator car in the shaftway, means for moving the elevator car, a gate on the elevator car, sliding doors for the shaftway openings, a set of toggle levers for each of the shaftway doors for controlling the movement of the door and locking the doors in the closed position, one of the levers on the sets having a bell crank lever portion, means on the elevator car gate adapted to cooperate with the bell crank lever to break the toggle lock and move the bell crank lever to open the door in accordance with the movement of the car gate, and means common to all the shaftway doors for controlling the closure thereof.

9. In an elevator system, a shaftway having a plurality of openings thereto, an elevator car in the shaftway, means for moving the elevator car, a gate on the elevator car, sliding doors for the shaftway openings, a set of toggle levers for each of the shaftway doors for controlling the movement of the doors and locking the doors in the closed position, one of the levers on the sets having a bell crank lever portion, means on the elevator car gate adapted to cooperate with the bell crank lever to break the toggle lock and move the bell crank lever to open the door in accordance with the movement of the car gate, another of said levers having a coun-

terweight and tail member, a common member under tension cooperating with the tails of said levers, means comprising a controlled spring for applying a force for the closure of said shaftway doors, and means cooperating with said member under tension for locking out the elevator car operating means when a shaftway door is open.

In witness whereof, I hereunto subscribe my signature.

NILS O. LINDSTROM.
